ABSTRACT

Good yields of high-quality motor fuel and jet fuel are obtained by solvent extracting a gas oil to produce a paraffin-rich raffinate and an aromatic-rich extract, hydrocracking the raffinate using a catalyst having an amorphous support, separately hydrocracking the extract using a catalyst containing a crystalline zeolitic support and recovering jet and motor fuels from the respective hydrocracker effluents.

9 Claims, No Drawings

PRODUCTION OF MOTOR AND JET FUELS

This invention is concerned with the production of gasoline and jet fuel. More particularly it relates to a method for the simultaneous production of jet fuel and gasoline.

Up until recently gasoline or motor fuel was by far the greatest demand product of the petroleum industry and accordingly it was desirable to get the maximum yield of gasoline per barrel of crude oil. To this end, most refineries were designed to convert those fractions boiling between about 450° F. and the lube oil range, i.e., the gas oil fractions, into gasoline and this was accomplished, for the most part, by fluid catalytic cracking. In the cracking of petroleum fractions, it is customary to recycle unconverted material to the cracking unit but eventually this recycled fraction, known as cycle gas oil, becomes so refractory and difficult to crack that a portion of it is withdrawn and sold as distillate fuel. However, with the advent of jet engines, fractions having an initial boiling point of from 350°-400° F. and an end point of about 525° F. have come into great demand as jet fuels. It has therefore now become customary to charge virgin gas oils to fluid catalytical cracking units and recover from the cracking unit as product bath gasoline and jet fuel and to recycle to the cracking unit that fraction of the effluent boiling above the jet fuel range. However, for the most part this process is unsatisfactory in that to meet the ever increasing jet fuel demands the gasoline end point must be compromised with jet fuel quality and/or product demands. This generally results in a gasoline having an end point of about 350° F. which means an overall reduction in the amount of gasoline produced. Moreover, because of its low luminometer number, the jet fuel fraction of the cycle gas oil is not completely satisfactory for use in jet aircraft engines.

It is an object of the present invention to provide a process for the production of motor fuel and jet fuel which comprises subjecting a petroleum hydrocarbon liquid having an initial boiling point of at least about 5,000° F. to solvent extraction to produce a paraffin-rich raffinate and an aromatic rich extract, hydrocracking the raffinate using a catalyst comprising a hydrogenating component on a noncrystalline amorphous support, recovering a jet fuel from the hydrocracked raffinate, separately hydrocracking the aromatic-rich extract using a catalyst comprising a hydrogenating component on a support comprising a crystalline zeolite and recovering a motor fuel from the hydrocracked extract.

The charge stocks used in the process of our invention include any hydrocarbon oil boiling above about 500° for example atmospheric gas oils, vacuum gas oils, atmospheric residua and the like. The preferred starting materials are virgin atmospheric gas oils and cycle gas oils obtained from the fluid catalytic cracking units.

The charge is subjected to solvent refining using a solvent having an affinity for aromatics such as SO₂, furfural, N-methyl pyrrolidone and the like. solvent dosages may range from 75-600 percent depending on the solvent and the charge stock. Temperatures of 50°-250° F. may be used also depending on the solvent and charge stocks. Preferred solvents are fufural of N-methyl pyrrolidone used at dosages of 75-300 percent and temperature of about 75°-150° F.

The raffinate after being stripped of residual solvent is hydrocracked by being brought into contact with a hydrocracking catalyst at a temperature between about 450° and 900° F., a pressure between about 500 and 5,000 p.s.i.g., a space velocity between 0.2 and 10 and a hydrogen rate of 2,000-30,000 SCFB. Preferred conditions are temperatures between 550° and 850° F., pressure of 1,000-2,500 p.s.i.g., space velocities between 0.5 and 3 and hydrogen rates between 4,000 and 20,000 SCFB.

The catalyst used for the hydrocracking of the raffinate comprises a hydrogenating component on an amorphous support. The hydrogenating component may comprise a Group VII metal or compound thereof either alone or in conjunction with a Group VI metal or compound thereof. When the hydrogenating component is a noble metal such as platinum,

palladium, sodium and the like, it is used in amounts between 0.1 and 5 percent, preferably between 0.2 and 1 percent based on the weight of the catalyst composite. When the hydrogenating component comprises an iron group metal or compound thereof, it may be used alone but preferably it is used in conjunction with a Group VI metal such as molybdenum or tungsten or compounds thereof. In such event, the iron group metal may be present in an amount between about 2-20 percent, preferably 5-10 percent by weight based on the catalyst composite and the Group VI metal may be present in an amount between about 5 and 35 percent, preferably between 6 and 25 percent by weight. Examples of combinations of Group VI and Group VIII metals are cobalt-molybdenum, nickel-molybdenum and nickel-tungsten. Advantageously the catalyst contains a minor amount of halogen such as 0.1-5 percent fluorine or chlorine.

The support for the catalyst used in the hydrocracking of the raffinate is composed of one or more amorphous inorganic oxides such as silica, alumina, zirconia, magnesia and the like. The preferred support is a mixture of silica and alumina containing from about 50-80 percent silica and 50-20 percent alumina by weight. A preferred catalyst contains 6 percent nickel and 19 percent tungsten on a support composed of 73 percent silica and 27 percent alumina. Advantageously, the catalyst is sulfided prior to use.

After the solvent has been removed from the extract as for example by distillation and stripping, the extract is subjected to hydrocracking. The conditions used for the hydrocracking of the extract such as temperature, pressure, space velocity and hydrogen rate are substantially the same as those used for the hydrocracking of the raffinate. However, the catalyst which contains a hydrogenating component such as (and which may be the same as) that of the catalyst used for the hydrocracking of the raffinate also contains a support which includes about 8-60 percent by weight of the support of a crystalline zeolitic alumino silicate. The crystalline portion of the support has substantially uniform pore openings of from 6-15 Angstroms and has an alkali metal content of less than 5 percent and preferably less than 1 percent. Suitably the crystalline portion of the support may be prepared by subjecting zeolite Y to ion exchange treatment with a solution of an ammonium salt to reduce the alkali metal content to about 3 percent. The zeolite is then washed, dried and calcined at a temperature of about 1,200° F. for several hours the calcined zeolite is then subjected to a second ion exchange treatment with a solution of an ammonium salt to reduce the alkali metal content to less than 1.0 percent, washed, dried and again calcined at a temperature of at least about 1,000° F. for several hours. The zeolite is then mixed with an amorphous inorganic oxide to provide the support for the hydrogenating component. Preferably, the balance of the support comprises a mixture of silica and alumina containing from 50-80 silica and 50-20 percent alumina. A preferred catalyst contains 6-8 percent nickel and 22 percent tungsten on a support containing 24 percent decationized zeolite Y, 57 percent silica and 19 percent alumina.

The effluents from the two hydrocracking units may be combined and fractionated to recover a motor fuel fraction and a jet fuel fraction, that portion of the effluent boiling above the jet fuel range being recycled to a fluidized catalytic cracking unit. Alternatively the effluents may be fractionated separately to recover motor and jet fuels with recycle of the unconverted material. In a preferred embodiment the hydrocracked product boiling above the jet fuel range, whether obtained from the raffinate or the extract is recycled to the solvent extraction zone.

When the charge to the system has a relatively high basic nitrogen content e.g., above about 100 p.p.m. nitrogen, it may be subjected to a denitrogenation treatment such as by contacting the charge with a catalyst such as nickel molybdate on alumina, in a manner well known to the art, to convert the nitrogen therein to ammonia which is removed prior to the solvent extraction step. However when the catalyst used for

the hydrocracking of the extract is composed of nickel and tungsten on a zeolite containing base as described above, then it is not necessary to subject the entire charge to a denitrogenation and it is sufficient to subject only the raffinate to nitrogen removal prior to hydrocracking. The nickel tungsten sulfide zeolite-based catalyst is particularly resistant to nitrogen poisoning and therefore the extract need not be given this additional treatment.

The hydrogen used in our process need not be pure. Hydrogen of 70 percent purity may be used but a hydrogen purity of at least 85 percent is preferred.

The following examples are given for illustrative purposes only.

Charge A is an atmospheric gas oil obtained from South Louisiana Light Regular Crude and Charge B is a cycle gas oil

TABLE III

Charge A is subjected to solvent extraction with furfural (containing 5 percent water) at a dosage of 75 volume percent and a temperature of 90° F. to obtain a yield of 79.5 volume percent of a raffinate containing 8.8 volume percent aromatics and 20.5 volume percent of an extract containing 80.0 volume percent aromatics. Solvent extraction of Charge B with furfural (5 percent water) at a dosage of 100 volume percent and a temperature of 90° F. yields 66.7 volume percent of raffinate containing 17.1 percent aromatics and 33.3 volume percent of extract containing 80.0 volume percent aromatics.

Hydrocracking conditions for the extracts and raffinates appear below in Table II. In each case for the hydrocracking of the extract the catalyst contains 7.9 weight percent nickel oxide and 24.7 weight percent tungsten oxide on a support containing 24 percent decationized zeolite Y, 57 percent silica and 19 percent alumina whereas the catalyst for the hydrocracking of the raffinate contains 6.5 percent nickel, 21 percent tungsten, 51 percent silica, 18 percent alumina and 1.5 percent fluorine. Also, in each case, the catalyst is sulfided prior to use.

Yields from the hydrocracking of the raffinates and extracts in terms of volume percent based on the total charge appear in Table III.

A comparison of the gasoline produced by the various procedures exemplified above appears in Table V. Column 1 represents the process of our invention in which the charge is solvent extracted and the raffinate and extract hydrocracked separately using amorphous and zeolite based catalysts respectively. Column 2 represents the process in which the total charge is hydrocracked over the zeolite-based catalyst and Column 3 in which the total charge is hydrocracked over the amorphous catalyst.

Table VI below shows the jet fuel quality comparison between jet fuels prepared by our process and those prepared by hydrocracking the charge. In Table VI Columns 1 and 3 show the characteristics of the product when the total charge is hydrocracked using a sulfided nickel tungsten silica alumina catalyst and Columns 2 and 4 when the raffinate is hydrocracked using a sulfided nickel tungsten on silica-alumina catalyst (Table III).

From the foregoing it can be seen that the process of our invention produces motor fuel and jet fuel in greater yields and of better quality than conventional processes.

It is also possible to recycle unconverted material into the system. For example that portion of the hydrocracked raffinate boiling above the jet fuel range may be recycled to the catalytic cracking zone, to the solvent extraction zone or to the raffinate hydrocracking zone. Similarly that portion of the extract boiling above the motor fuel range may be recycled to the catalytic cracking zone, the solvent extraction zone or to the extract hydrocracking zone. Various other modifications of the invention as hereinbefore set forth may be made without departing from the spirit and scope thereof and therefore only such limitations should be imposed as are indicated in the appended claims.

We claim:

1. A process for the simultaneous production of gasoline and a jet fuel fraction which comprises subjecting a gas oil to solvent extraction to produce a paraffin-rich raffinate and an aromatic-rich extract, hydrocracking the raffinate using a

catalyst comprising a hydrogenating component on a noncrystalline amorphous support, recovering a jet fuel fraction from the hydrocracked raffinate, separately hydrocracking the extract using a catalyst comprising a hydrogenating component on a support comprising a crystalline zeolite and recovering gasoline from the hydrocracked extract.

2. The process of claim 1 in which the crystalline zeolite has an alkali metal content of less than 1 percent by weight.

3. The process of claim 1 in which the zeolite is present in the support in an amount between 8 and 60 percent by weight of the support.

4. The process of claim 1 in which each hydrogenating component comprises a Group VIII metal or compound thereof.

5. The process of claim 4 in which the catalyst used for the hydrocracking of the raffinate comprises nickel and tungsten.

6. The process of claim 4 in which the catalyst used for the hydrocracking of the extract comprises nickel and tungsten.

7. The process of claim 1 in which the gas oil is derived from a catalytic cracking reaction and that portion of the hydrocracked raffinate boiling above the jet fuel range is returned to the catalytic cracking zone.

8. The process of claim 1 in which that portion of the hydrocracked extract boiling above the gasoline range is returned to the solvent extraction zone.

9. The process of claim 2 in which the crystalline zeolite has been prepared by subjecting zeolite Y to a treatment comprising ion exchange with a solution of an ammonium compound, calcination, a second ion exchange with a solution of an ammonium compound and a second calcination.
